Attorneys:

UNITED STATES PATENT OFFICE.

FREDERICK-GEORGE FISHER, OF QUINCY, MASSACHUSETTS, ASSIGNOR TO NATIONAL FOLDING BOX COMPANY, OF NEW HAVEN, CONNECTICUT, A CORPORATION OF NEW JERSEY.

DISPLAY BOX.

Application filed March 24, 1920. Serial No. 368,227.

To all whom it may concern:

Be it known that I, FREDERICK-GEORGE FISHER, a citizen of the United States, residing at Quincy, in the county of Norfolk and 5 State of Massachusetts, have invented new and useful Improvements in Display Boxes, of which the following is a specification.

My invention relates to paper boxes of the sort which are used, not only for packaging 10 goods, but also to display and advertise the contained goods in places such as counters and shelves of stores, etc. The main object of the invention is to provide such a box with an easel or brace, so formed and connected to the box that it may be folded flat 15 against the bottom of the box, and will thence come automatically into place to support the box on an inclination when the box is laid bottom downward on a supporting 20 surface.

A further object is to combine such an easel with a collapsible or knock-down box, and a display tab, made from box board, or equivalent material, with economy of material.

In the drawings furnished herewith,—

Figure 1 represents the blank from which the body of the box is made.

Figure 2 is the blank from which the 30 easel and display tab are formed.

Figure 3 is the box partly made up with the display tab and easel attached thereto, and constituting a part of the box.

Figure 4 is a longitudinal section of the 35 box in display position.

Figure 5 is a longitudinal section of the box showing the easel and the display tab laid down, folded against the box.

Figure 6 is a perspective view of the box, 40 showing the manner in which the piece furnishing the easel and the display tab is fastened to the rest of the box.

Figure 7 is a perspective view of the bottom of the box.

Figure 8 is a perspective view of the box 45 folded for shipment or storage.

Like reference characters indicate the same parts in all of the figures.

The formation of the blanks from which 50 my box is to be made up, as will be noted by reference to Figures 1 and 2, permits them to be so cut that the unavoidable waste of material is reduced to the minimum.

The blank for the box body, shown in 55 Figure 1, comprises the following parts: side panels 10, an end panel 11, and bottom panels or sections 12, 13 and 14, attached to the sides and end referred to above.

The side panels 10 are each integral with 60 the end panel 11 at one end, and have formed on their free ends, tabs 15. These tabs 15 are for the purpose of securing the side members to the easel strip, later described, which forms one end of the box. 65 To the side panels 10 and the end panels 11 are preferably joined, respectively, reinforcing panels 16 and 17, which may be folded down on lines *a*—*a* against the sides 10 and end 11, and secured thereto by adhesive or other means, to strengthen and stiffen said sides and end. However, this feature may be omitted altogether without departure from the essence of the invention.

The easel strip or blank, as shown in Figure 2, is rectangular in outline and is creased or scored to provide hinge or folding lines, so as to be bendable into a form suitable for a support. Said folding lines define the following panels: the panel or 75 display tab 18 which, when the box is formed or made up, is adapted to be bent down over the contents of the box, or bent back to display a legend or advertisement 80 printed thereon; an end panel 19, adapted to be secured to the side panels 10 by means of tabs 15, whereby to serve as the end wall 85 of the box opposite to the wall 11; and panels 20, 21, 22, 23 and 24, adapted to be so bent, as to make the easel member 90

In completing the easel the panels are folded back, always in the same direction, on the bending lines *b*, *c*, *d*, into a substantially triangular figure, or, more exactly, the form of a triangular prism, as shown in Figure 95 4, with the corner established by the line *d* near the bottom of the box. Then the panel or lip 24 lies against the panel 20, to which it is fastened, preferably by adhesive, or permissibly by the other sorts of fastenings. This makes a strongly braced construction, in which the panel 20 forms that part or section of the easel which actually holds the box at an inclination, the widely separated angles formed by bending the 105 easel on the lines *b* and *c* form a broad base to rest on the supporting surface, and firmly establish the position of the panel 20, the

panel 23 provides a brace, and the connected panels 21 and 22 form a tying section to limit the distance to which the supporting and bracing sections may spread apart. The bending line *e* between the panels 21 and 22 establishes a hinge on which said tying section may be bent to permit collapsing of the easel when it is laid against the bottom of the box. Between the easel so formed as a whole, and the panel 19, which provides the adjacent end wall of the box, is the bending line *f*, which provides a hinge between the easel and the body of the box, enabling it either to be laid against the box bottom, as shown in Figure 5, or to occupy the supporting position, as shown in Figures 4 and 6.

By reason of the construction just described, when the box is held raised above any surface on which it is intended to be placed, the easel will drop by gravity, and will spread by the resilience of its parts into approximately the position shown in Figure 4, thereby automatically so placing itself as will hold the box at an inclination when the latter is laid on the supporting surface. The weight of the box and its contents applied upon the easel, so far from having any tendency to collapse the latter, tends rather to spread the base corners formed by the bending lines *b* and *c* further apart, and to increase the stability of the easel.

In assembling these blanks into the commercial article, the side panels 10 are secured to the end panel 19 of the easel blank by means of the tabs 15, (which are glued or stapled to the panel 19), and the easel panels are folded upon each other, and the lap 24 is secured to panel 20, as indicated above. Panels 16 and 17 are turned in and secured to the sides and end member. These steps need not be performed in the precise order named, however, but may be taken in any order preferred by the maker. The device is now completed as a commercial article, and may be folded, as in Figure 8, for delivery in packages to the user.

The box is made up for use, by forming the sides and ends into a rectangle, bending the panel or flap 13 inward and then bending the flaps or panels 12 and 14 over against said flap and securing them. It is immaterial whether flap 12 or flap 14 is first bent over, inasmuch as the two are identical in construction. In order to hold these panels or flaps 12 and 14 in place, there are located in each panel or flap, slots or slits 25, and on the outer ends, tongues 26, adapted to pass through said slits. Should the panel 12 be folded inside of panel 14, the tongues 26 thereon will be passed outwardly through slots 25 on panel 14, and the tongues 26 on panel 14 will be passed inwardly through slots 25 on panel 12.

When the box is so made up, the easel is in position to either be folded under the box, as shown in Figure 5, or to assume the operative position, as shown in Figure 4; and, as stated above, the natural tendency of the easel is to assume the operative position. Therefore, when the user holds the box suspended bottom downward in air, the easel will automatically come into place to tilt one end of the box, and hold such end raised, when the box is laid down. This is a great convenience, as it avoids need of any pains being taken to place the easel in its supporting position.

When, however, it is desired to have the box rest flat on a table, counter, shelf, or other support, the easel may be folded as shown in Figure 5, and be placed to rest flat on said support.

The panel 18 constitutes a display flap, which as stated above, may lie flat forming a partial cover to the top of the box; or may be turned back, as shown in Figure 4, to a position where it is adapted to display any legend or advertisement which may be printed upon it. This box may be used with or without a cover or outer casing, for storage or shipment of goods.

Although I have described that part of my invention which is embodied in the easel as being associated with a collapsible or knock-down box, it is to be understood that said invention is not limited to that particular use or association, but may be applied to any and all other sorts of boxes as well. Also, that when applied to a knock-down box, the easel and box body may be made out of one integral blank.

What I claim is:

1. The combination with a box of an easel hinged to one end of the box and adapted to hold such end raised when resting on a supporting surface, and comprising divergent supporting and bracing sections and a tying section, so arranged and connected with the box at the end thereof which is thus raised that the supporting and bracing sections both extend therefrom to the supporting surface, and the tying section extends between the lower ends of the other two sections, limiting the distance to which they can spread apart.

2. A box having side, end, and bottom panels, and in combination therewith, an easel of boxboard hinged to one of said panels and itself having panels arranged in triangular prism form with one of the panels being a tying section hinged to fold inwardly between the other two, the hinge whereby the easel is connected to the box being at the apex or angle opposite to said tying section, whereby the entire easel is adapted to be collapsed and laid against one of the panels of the box, or to hang from the box when left free and automatically assume

a position for holding that end of the box to which it is hinged elevated above a supporting surface on which the box may be laid.

5. 3. The combination with a box, of an easel having a triangular prism form with three panels, hinged at one of its angles to the box adjacent to one end thereof, whereby the two panels between which the said angle 10 is included are adapted to support the box in an inclined position with that end to which the easel is attached raised above the opposite end, the aforesaid two panels then extending from the box at different angles 15 thereto, and the third panel of the easel being a tying section displaced from the box at all points and limiting the spread of the first two panels, said third panel having a bending line so disposed that it is adapted 20 to fold inwardly and permit both the other panels to be laid close to the box bottom.

4. The combination with a box of an easel having three panels in triangular prism formation one of which panels is a tying section 25 between the other two and is scored to fold inwardly permitting the other two panels to be placed close together, and the entire easel being in one piece with a portion of the box structure and hinged to the box at a point 30 distant from one end of the box in a manner permitting such distant end to be placed on a supporting surface and the corners of the easel between which said tying section is situated to be also placed at the same time on 35 said surface, whereby the point of the box at which the easel is connected is held away from the surface.

5. A box having a support movably connected to one of its ends, said support being 40 of boxboard arranged in the form of a triangular prism hinged at one of its angles to the box, its other two angles being adapted to rest on a surface upon which the box is placed, and the section or panel of the support 45 between the last two named angles having a bending line on which it may be folded to permit the side panels of the support to be brought together and against the box.

6. A collapsible box including in its construction panels adapted to form a bottom 50

and upstanding walls, and an extension projecting from one of said panels and hinged thereto at one of the bottom edges of the box; said extension being progressively bent on separated folding lines parallel to 55 said edge into triangular prism formation, which formation provides a triangular easel hinged at its apex to the box, whereby it may swing as a unit relatively thereto, and having its sides which diverge from said 60 apex hinged relatively to one another; the side opposite to the apex being creased to permit collapse of the easel.

7. A display box having a support comprising two panels adjacent to one another 65 and hinged to the box, and a tying section hinged to said panels at a distance from the box, said tying section being foldable to permit placement of both said panels close to a 70 surface of the box.

8. A display box having a support comprising two panels adjoining one another at one edge and hinged so that parts of said panels remote from such adjoining edges may be swung together and apart, and a 75 tying section hinged to said panels at a distance from the box, said tying section being foldable to permit placement of both panels close to a surface of the box, and the entire support being hinged to the 80 box adjacent to one of the bottom edges of the box and also adjacent to said adjoining edges of the panels.

9. The combination with a box of an easel having three members in triangular prism 85 formation, one of which members is a tying section between the other two permitting the other two members to be placed close together, and the entire easel being hinged to the box at a point distant from one end of 90 the box in a manner permitting such distant end to be placed on a supporting surface and the corners of the easel between which said tying section is situated to be also placed at the same time on said surface, whereby the 95 point of the box at which the easel is connected is held away from the surface.

In testimony whereof I have affixed my signature.

FREDERICK-GEORGE FISHER.
